BAG FRAME FASTENER ATTACHING MEANS

Walter I. Jones, Arlington, Mass., assignor to
United-Carr Fastener Corporation, Cambridge,
Mass., a corporation of Massachusetts

Application February 17, 1932, Serial No. 593,596

4 Claims. (Cl. 150—29)

My invention aims to provide improvements in bag frame fastener-attaching means.

In the drawing which illustrates preferred embodiments of my invention:—

Figure 1 is a perspective elevation view of an improved form of bag frame structure to which my invention is applicable;

Fig. 2 is an enlarged section taken through the bag frame and showing parts of the fastener-attaching means;

Fig. 3 is a plan section taken on the line 3—3 of Fig. 2 to show the manner of securing the attaching means to the frame structure;

Fig. 4 is a sectional view of a frame member and a fastener-attaching means prior to complete assembly; and

Fig. 5 is a sectional view similar to Fig. 4 of a second form of attaching means.

My invention is particularly, though not exclusively, adapted for use in securing separable fastenings to frame members of handbags.

In the drawing, I have shown a pair of U-shaped frame members 1 and 2 (Figs. 2 and 3) of usual construction and hinged together for movement of one relative to the other. The frame members 1 and 2 which I have selected for illustration and description are U-shaped in cross-section with the open ends of the U facing outwardly (Figs. 1 and 2).

The particular separable fastening means shown is for illustration only because many snap-acting types of fastening members may be attached in the manner which constitutes my invention and which I shall now describe. The attaching means illustrated fits into the U-shaped frame members and when attached is substantially L-shaped or reversed L-shaped, depending upon the frame member to which it is secured. Each attaching member has an upwardly projecting portion 3 located adjacent to the inner wall 4 of the frame member and being free to yield relative thereto. At the lower end of the portion 3 there is provided a flange portion 5 which is adapted to fit between the upstanding walls of the frame member adjacent to the bottom wall 6. In the construction illustrated in Figures 1 through 4 inclusive the attaching member is provided with a second flange portion 7 extending from the outer edge of the first mentioned flange portion 5 and provided with a frame-engaging portion 8 at its free edge which is of less width than the flange portion 7, as illustrated in Fig. 3. When the attaching member is secured in position this frame-engaging portion 8 extends into a slot 9 in the inner wall 4, thereby

preventing the attaching part from falling out of the frame member.

The combined length of the flange portion 7 and the frame-engaging portion 8 is greater than the width of the space between the upstanding walls of the frame member and therefore I use a novel method of securing the device in position.

Prior to securing the attaching member to the frame the flange 7 and frame-engaging portion 8 extend downwardly at an angle from the flange 5, as best illustrated in Fig. 4. With this arrangement the device can be inserted between the walls of the frame member 1 until it reaches the position shown in Fig. 4. Then a suitable tool may be

used to engage the flange 5 and press the device downwardly, thereby flattening the flange portion 7 and forcing the frame-engaging portion 8 to enter the slot 9 securely to attach the device as illustrated in Fig. 2. The particular construc-

tion of the device illustrated in Figs. 1 through 4 is desirable because the fastening means 10 located at the upper end of the portion 3 can move readily to make snap engagement with the fastening portion 11 on the other member due to the fact that the attaching member may yield

throughout the length of the flange 5 and the portion 3. Furthermore, the action of the device is such that there is a downward pressure upon the flange portion 7 adjacent to that end which is not connected to the frame, while there is an upward pressure at that end which is secured to the frame. In this manner the device is securely attached and cannot become disengaged accidentally.

In Fig. 5 I have shown another form of attaching means which has a single flange 12 at the bottom provided with a frame-engaging extension 13 adapted to engage in a slot 14 in the outer wall. The manner of attachment of this device is substantially the same as described in connection with Figs. 1 through 4. While this device is somewhat more simple in construction than the first described device and may be useful, it is not as desirable as the former because the yielding action tends to move the frame-engaging portion 13 laterally out of the slot 14.

While I have illustrated and described preferred embodiments of my invention, I do not wish to be limited thereby, because the scope of my invention is best defined by the following claims.

I claim:

1. A bag frame structure comprising, in combination, a pair of frame members hinged together at their ends, each of said frame members being U-shaped in cross-section, separable fasten-

- ing members securing the frame members together, one of said fastening members having a substantially L-shaped portion located within the space of one of said U-shaped frame members and having a frame-engaging portion extending therefrom into an aperture in one of the upright walls of the U-shaped frame member to secure the L-shaped portion to the frame. 5
2. A bag frame structure comprising, in combination, a pair of frame members hinged together at their ends, each of said frame members being U-shaped in cross-section, separable fastening members securing the frame members together, one of said fastening members having a substantially L-shaped portion located in one of said U-shaped frame members and having a frame-engaging portion extending therefrom into one of the upright walls of the U-shaped frame member to secure the L-shaped portion to the frame. 10
- 15 3. A bag frame structure comprising, in combination, a pair of frame members hinged together at their ends, each of said frame members being U-shaped in cross-section, separable fastening members securing the frame members together, one of said fastening members having a substantially L-shaped portion located in one of said U-shaped frame members, said L-shaped portion having a double thickness at the bottom and the frame-engaging portion extending from the lower portion into the wall of the frame adjacent to the upright portion. 20
- 25 4. A bag frame structure comprising, in combination, a pair of frame members hinged together at their ends, each of said frame members being U-shaped in cross-section, separable fastening members securing the frame members together, one of said fastening members having a substantially L-shaped portion located in one of said U-shaped frame members, said L-shaped portion having a bendable bottom portion flattened against the bottom of the U-shaped frame member and provided with means extending laterally therefrom into one of the upright walls of the U-shaped frame member to secure the fastening member in position relative thereto. 30
